3 Claims

ABSTRACT OF THE DISCLOSURE

A railway car journal lubricator having a central section and two wing sections located at each side of the central section; a flexible upper outer cover of cloth material having a lock stitch looped-pile, or nap outer surface for contacting the journal; an open mesh flexible cloth material covering the bottom portion of the lubricator; a wicking cloth element positioned adjacent the inner surface of the open mesh bottom cover wherein the wicking cloth has each of its outer ends in multi-ply relationship and secured within pockets formed in the two wing elements between the upper and bottom cover elements; the upper and lower cover elements in the central section of the lubricator being held in space relationship by resilient core elements.

The present invention relates to an improved lubricator for journal bearings for railway cars.

The invention relates specifically to a lubricator for use with a segmented bearing for the journal and arranged in a journal box, surrounding the journal, between the bottom of the journal and the inner surface of the bottom of the journal box. The purpose of this type lubricator is to transmit by wicking and/or by capillary action lubricants from the bottom of the journal box to the underside of the journal. In this arrangement the journal box is utilized as an oil reservoir.

The primary object of the invention is to provide a structure that will greatly increase the flow of lubricant to the journal over lubricators of this general type in present day use.

Another object of the invention is to provide a lubricator with this additional action at very little additional cost over those presently in use.

A further object of the invention is to provide a lubricator of this improved type that may be readily substituted for the general types of lubricators now in use.

While several objects of the invention have been pointed out, other objects, uses and advantages will become more apparent as the nature of the invention is more fully disclosed which consists in its novel construction arrangement and combination of its several parts illustrated in the accompanying drawings and described in the detailed following description.

In the drawings:

FIG. 1 is a view partly in elevation and partly in section of the improved lubricator.

FIG. 2 is a vertical sectional view of the lubricator illustrating its position with respect to the journal and the journal box.

In referring to the drawings like reference characters are used to designate like and similar parts throughout the several views.

The lubricator is adapted to be used with a standard railway car journal and journal box wherein the journal box acts as a reservoir for the oil to be conveyed to the journal by way of the lubricator. Referring in particular to the drawings, the lubricator A is located within the journal box as illustrated in FIG. 2. The journal 10 is normally the extension of the car wheel axle. Supported

on the journal 10 is a segmentary bearing 14 which generally extends only about the upper portion of the journal and is housed with the journal within the journal box 8. The axle in turn being connected with means for supporting the railway car. The journal is spaced upwardly from the bottom surface of the journal box to provide space for the carrying of the oil supply 12 and the lubricator A extends between the bottom 8' of the journal box 8 and the under surface of the journal 10.

The lubricator is usually of rectangular form and is of such dimensions as to contact the full longitudinal length of the journal and to extend laterally to substantially contact the sides of the journal box for holding the lubricator in position beneath the journal.

The lubricator comprises in general, a flexible cloth upper cover portion 15 having a lock stitched looped-pile outer surface and a bottom cover 16 of an open woven material. The two covers are stitched together in such a manner as to form a central portion and a wing portion

on each side of the central portion. There are a pair of resilient core elements B and B' positioned within the central section, but is not limited thereto, as any convenient number of core elements may be used including a single core element. The upper cover member 15 is preferably of a material having a locked stitch, looped-piled or napped outer surface. The central resilient core elements are constructed preferably from a suitable resilient material such as natural or synthetic rubber, or the like. The upper cover element 15 is preferably constructed of one piece an cut to sufficient length to extend over the entire upper surface of the lubricator unit and between the central core members B and B' as shown at 15' and 15".

The lower cover member 16 is constructed preferably of a knitted open mesh cloth and extends along the bottom of the lubricating unit A, and up each of the two sides and beneath the wing elements C and C' cooperating with the upper cover to form pockets in the wing portions C and C'. However, these covers may be constructed of any suitable material.

Extend along and adjacent the interior surface of the bottom cover 16 there is a highly efficient wicking material 18 such as roving cloth. This wicking material, or roving cloth extends preferably completely along the bottom of the lubricating unit, up the side walls to where the bottom and top coverings are stitched together at each side of the central section and into the wing elements C and C'. The two covers and the roving cloth are stitched together at the bottom by stitches 19. The upper cover 15 is stitched together by stitches 20 adjacent the upper surface of the lubricator to form one side of two central pockets for the resilient core members B and B'. The core elements also have the function of absorbing oil and acting as an oil reservoir for the central cover portion. The upper and bottom covers are stitched along parallel lines by stitches 21 and 21' forming the central pockets in the central section of the lubricator. The two covers 15 and 16 are also stitched along their outer elongated edge by stitches 22 and 22' to form similar but smaller pockets in the wings C and C'. The mesh material used as the bottom cover allows for the rapid movement of the oil therethrough to the wicking material to be delivered to the wing elements C and C'.

The wicking material is of such length that it is folded, rolled, bunched or in other multi-ply form as shown in FIG. 1 for providing an oil reservoir for each of the wings C and C'. The oil is wicked up the sides of the unit by the wicking material and into the wing area where it is held in readiness to be transmitted by capillary action through the cover element 15 to the loop-pile to the journal 10, lubricating the same.

There is provided a strap 23 stitched to the cover elements and surrounding the core elements B and B' in

which there is provided a grommet (not shown) and in which a conventional hook may be placed for removing the lubricating unit from the journal housing when desired.

In operation the lubricator is placed within the journal box 8 as shown in FIG. 2. The central section of the lubricator and the resilient cores B and B' are placed beneath the lower surface of the journal, the cores being of such thickness as to be slightly compressed to insure that the loop-pile surface of the upper cover 15 are always in contact with the journal. The wing elements C and C' extend outwardly from the central portion along the outer edges, contact the sides of the journal box to hold the lubricating element in position under the journal. The wing elements C and C' are also in contact with the journal. Oil is induced into the journal box through an appropriate opening to a level extending below the journal to a depth of several inches. The core and top cover with its loop piles will attract a certain amount of oil upwardly through the center of the unit to the upper surface of the upper cover where it will contact the surface of the journal. However, even though of less cross sectional area, the wings supply a large amount of lubricant to the journal by wicking the oil directly into the wings by the wicking material 18 into the multi-ply wicking material 18' carried in the wing elements where the oil is stored to be conveyed by capillary action through the upper cover 15 of the wing members where it will be deposited on the journal.

The oiling of the journal is greatly enhanced by the present arrangement. The oil moves rapidly through the bottom mesh cover to the wicking material where it is conveyed to the multi-ply pile 18' in the wing elements.

I claim:

1. A journal lubricator for use in railway car journal boxes in which the journal box serves as an oil reservoir wherein oil is lifted from the reservoir by a wicking material to the underside of the journal, comprising:

- (a) a central section and a hinged wing portion on each side of the central section;
- (b) said central section and hinged portions comprising a flexible cover of woven material having at least a nappy upper surface and formed into a plurality of transverse pockets extending substantially the longitudinal length of the journal when mounted within a journal box;
- (c) a sheet of wicking material extending parallel with the bottom portion of the cover and adjacent the inside surface thereof, the opposite ends of the wicking material terminating in each of the wing portions; and
- (d) the portion of the wicking sheet extending into the wing portions being in multi-ply relationship to form an accumulation of the said wicking material for the storage of oil therein.

2. A journal lubricator as claimed in claim 1 wherein the cover over the upper surface of the lubricator is formed with a lockstitch loop-pile extending outwardly from its upper surface and the cover for the bottom of the lubricator being of a woven mesh material for allowing the oil to flow readily therethrough to the wicking material.

3. A journal lubricator as claimed in claim 1 wherein the upper cover extends downwardly through the center of the central section to form a double pocket longitudinally of the said section and a resilient core element position within each of the said pockets for keeping the central portion of the lubricator normally in expanded position.
